RETURN BEND FOR OIL STILLS AND
THE LIKE

Henry E. Muchnic, Atchison, Kans., assignor to
The Locomotive Finished Material Company,
Atchison, Kans., a corporation of Kansas

Application November 5, 1934, Serial No. 751,531

2 Claims. (Cl. 138—95)

My invention relates to headers or return bends especially intended for oil cracking stills and relates more particularly to the closure devices for the return bends and means whereby the latter 5 may be removed.

The invention has as a primary object the provision of construction wherein effective closure for the openings which are aligned with the tubes may be obtained by means of simple gaskets instead of by means of tapered plugs and plug-seats 10 as heretofore employed.

Another object of my invention is to provide a structure wherein the relation between the closure effecting elements is such that pressure will 15 be applied directly over and against the joint forming gasket, or closely adjacent thereto.

Another object of my invention is to provide a construction wherein the over-all height or dimensions of the fixture or return bend is greatly 20 reduced.

A further object of the invention is the provision of a construction wherein the closure element or plug and the wall of the return bend or housing may be provided with interengaging surfaces 25 whereby rotation of the closure element or plug will be prevented during movement of the pressure applying means.

A further object of the invention is the provision 30 of a closure element or plug having a puller tool engaging surface whereby easy attachment of the plug puller thereto may be readily effected; the plug being also formed to provide a limit stop for the puller to prevent too far rotative movement of the puller and thus ensure an even or 35 uniform pulling effect on the plug.

The foregoing enumerated objects and the advantages inherent in the invention will all be more readily comprehended from the following detailed description of the accompanying drawings 40 wherein:

Figure 1 is a partial plan and partial sectional view of the construction as illustrated in Figure 2; the section being taken substantially on line 1—1 of Figure 2 as viewed by the arrows.

Figure 2 is a section taken substantially on line 2—2 of Figure 1, as viewed by the arrows.

Figure 3 is a plan with portions broken away, showing application of the plug puller.

Figure 4 is a sectional view taken substantially 50 on the line 4—4 of Figure 3.

Figure 5 is a sectional detail taken on the line 5—5 of Figure 3 as viewed by the arrows.

Figure 6 is a longitudinal section of a portion of header or return bend showing a modified form 55 of pressure applying member.

Figure 7 is a similar view illustrating a modification of cap member with an auxiliary pressure applying member.

Figure 8 is a similar view showing a modified form of closure member or plug.

The exemplification of the invention as disclosed in Figures 1 and 2 is shown consisting of a return bend or header 10 having a body portion provided with an arcuate or return bend bore or passage 11, the ends whereof receive the ends of 10 a pair of pipes or tubes of which merely portions are shown at 12, 12; these tubes being secured in the header in a suitable manner.

The opposite wall of the header 10, at points substantially in alignment with the tubes 12, is 15 provided with bores or openings 13, 13.

These bores 13, communicate with the arcuate channel 11 and thus provide access to the tubes 12 for the periodical cleaning especially necessary 20 in oil cracking stills.

The wall of the header and encircling the bores 13 is provided with the annular gasket receiving grooves 14 which are intended to receive a suitable gasket 15 whereby a fluid tight closure is effected when the gasket has been subjected to proper 25 pressure.

This side or wall of the header 10 is also provided with the outstanding annular walls 16 defining a greater circumference than the annular gasket receiving grooves 14; the annular walls being 30 preferably united as shown by the web portion 17; while the inner circumferential surfaces of these walls are preferably screw-threaded throughout as shown in Figure 2. These annular walls 16 are 35 of a size to provide a sufficient threaded surface whereby the pressure applying members 18 may obtain sufficient purchase.

The bores 13 are intended to receive the closure members or plugs 19, of a deflector type wherein the inner ends are formed arcuate in keeping with 40 the curvature of the channel 11; and these plugs preferably are made tapering as shown.

In order that the closure elements or plugs 19, especially when made with the inner ends constituting a portion of the arcuate channel 11, may 45 be properly positioned in the bores 13, I have shown each closure member or plug preferably provided with the radially disposed extension or lug 20, which is so arranged, relative to the slope or direction of curvature at the inner end of the 50 plug, that the positioning of the plug will be controlled.

The annular walls 16 are each provided with a slot 21 disposed throughout the width of the wall and communicating with the inner circum- 55

ference of the wall. These slots are adapted to receive the extensions or lugs 20 of the closure or plug members 19 as more clearly shown in Figure 1. It is apparent also that the slots and lugs will hold the plug members 19 against rotation which might be induced during screwing into place of the pressure applying members 18.

The pressure applying members are externally threaded so as to screw into the annular pockets 10 provided by the annular walls 16; and the outer surfaces preferably provided with an angular or wrench receiving boss portion 22.

The inner ends of the pressure applying members or cap nuts 18 are shown hollowed out or dished at 23 in order to provide clearance for and to receive the puller tool grasping flanged boss or enlargement 24.

This boss or enlargement 24 is shown preferably provided with the sectoral flanges 25, 25 which 20 provide grasping surfaces for a suitable puller as for example of the type shown in Figures 3, 4 and 5 and hereinafter described.

The parts are assembled by first providing the groove 14 with a suitable gasket 15 and then putting closure member or plug 19 in place. Where the plug is of the deflector type the lug 20 is brought to register with the end of slot 21 in the annular wall, allowing the closure member or plug to be forced toward its seat. The flange or cap portion 26 of the plug, on its inner surface, is also provided with an annular socket or groove 27, adapted to register with groove 14 in the wall of the header and to receive the annular gasket 15.

The cap or pressure applying member 18 is then 35 screwed into the threaded portion of the annular wall 16 so as to bring it into contact with the plug 19.

The inner surface of the cap member 18 is preferably formed with an annular bead 28 arranged 40 to engage the flange of plug member 19 directly opposite the groove 27 and hence in circumferential alignment with the gasket 15. The bead 28 is preferably formed with a short arc so as to afford a comparatively narrow bearing contact 45 with the plug-flange and hence reduce the frictional relation between cap or pressure applying member 18 and the plug 19 during pressure applying movement of member 18. Through the application of a suitable wrench or tool to the angularly formed boss 22, the cap member 18 may be 50 very tightly screwed down onto the plug member 19, causing a pressure resisting and fluid-tight closure to be effected through the medium of the gasket 15. As is apparent from the construction 55 shown, the pressure is applied in a relatively large circular plane directly in alignment with the gasket and with the main walls of the head so that distortion of the closure members or plugs is not likely during the high temperatures and pressures 60 to which return bends are subjected during still operation.

In oil still operation it is periodically necessary to clean the tubes and return bends and hence it becomes necessary in return headers of the general type here in question to remove the closure members or plugs 19, which, however, requires application of considerable power because of the "coking" or gumming up of the plugs.

It is necessary therefore to employ a suitable 70 tool whereby a direct pull on the plug may be exerted. The plugs 19 are therefore shown provided with the sectoral flanges 25, 25 in order to receive the bifurcations or jaws 29 of the puller element 30, see Figure 4. The ends of the jaws 75 29 are turned upwardly to engage beneath the

flanges 25, 25; and in order to ensure proper positioning of these jaws, I provide the bottom surfaces of the flanges 25 with a suitable limiting stop, such as a lug or depression or recess as shown at 31 on the lower sides of the flanges 25, 25, see 5 Figure 4. This prevents the too far turning of the puller during its application to the plug.

The shank portion of the puller 30 is shown screw threaded throughout and passes through a suitable opening in the yoke member 32 whose 10 ends are adapted to rest on the walls 16 of the header; the ends of the yoke member are preferably turned downwardly to prevent transverse movement of the yoke member.

Upon screwing down nut 33 on shank of puller 15 30, the puller will be drawn outwardly toward the yoke 32, when the nut 33 is in firm relation with the yoke, thereby causing the plug 19 to be drawn out of the header unit 10.

It is evident that a great pulling force is not 20 only obtained but the pulling force is also exerted in direct alignment with the longitudinal axis of the plug 19.

In Figure 6 I illustrate a modification wherein the extended wall 16 of the header or return bend 25 10 is also internally threaded and provided with a closure member or plug 19a, substantially similar to the construction shown in Figure 2. The header 10 is also shown with an annular groove 30 for reception of the gasket 15. The plug 19a has the outer surface of its pulled grasping boss or enlargement 24a preferably provided with a central arcuate socket at 34. The pressure applying member or cap 35 is externally threaded to screw 35 into the annular pocket formed by the extended 40 wall 16, with its outer surface provided with an angular or wrench receiving boss portion 36. The inner surface of the member 35 is somewhat cupped to permit it to have sufficient threaded engagement with the extended side wall. The 45 center of the member 35 is provided with an arcuate boss or enlargement 37 which is adapted to seat in the arcuate socket 34 of plug member 19a when the cap member 35 has been sufficiently 50 screwed into the pocket formed by the extended 45 wall 16. It is apparent that when cap member 35 is screwed down into the pocket the boss 37 will force the plug member inwardly and cause its 55 annular flange to compress the gasket 15 or to effect fluid-tight relation with the header. In 60 this construction, the plug is subjected to a centralized pressure and this pressure is applied during the single operation of applying the cap member.

In Figure 7 another modification is shown, 55 wherein the header 10 is also provided with an annular extended wall 16 disposed about the opening and this wall 16 internally threaded as shown in Figure 2. The annular pocket formed 60 by the wall 16 is intended to receive the pressure 65 applying member or cap 38, whose outer perimeter is screw-threaded to screw into the annular pocket. The inner side of the cap member is provided with an annular bead portion 39 disposed slightly beyond the threaded portion and adapted to engage with the flanged portion of the closure plug 19a when the cap member 38 is 70 screwed into the pocket formed by extended wall 16. The plug member 19a is also provided with an enlargement or boss 24a which is provided 75 with a depression or socket 34. The cap member 38 is centrally provided with a tapped opening extending therethrough to receive the screw-bolt 40, which seats in the socket or depression 34. It is apparent from this construc- 75

tion that in addition to the pressure on plug 19a exerted by cap member 38, pressure may also be centrally applied to the plug by means of screw-bolt 40.

- 5 Figure 8 illustrates a modification wherein the header element is not provided with an annular wall extended outwardly about the opening and the pressure applying cap member is eliminated. The header member 41 is shown provided with 10 the gasket receiving groove which receives the gasket 15. In this construction the plug member 42 has its annular flange 43 provided with a plurality of preferably equally spaced holes for passage of the stud-bolts 44 therethrough. The 15 stud-bolts screw into tapped holes 45 in the header member 41; and the flange of the plug member 42 is forced into fluid-tight relation with the gasket 15 (which also seats in a groove in the plug member 42) by nuts 46.
- 20 The nuts on all of the stud-bolts are preferably screwed down on the stud-bolts 44 to an equal degree so as to effect equal pressure on the flange of the plug member.

It is apparent that the fluid-tight relation between the headers and the plug members may be effected by different means or types of gaskets; the type illustrated being, however, thought to be very effective.

The constructions shown in the drawings are believed to be the best embodiments and have been described in terms employed for purposes of description and not as terms of limitation as structural modifications are possible and may be made without, however, departing from the 35 spirit of my invention.

What I claim is:—

1. In a return bend of the character described the combination of a header provided with a return passage whose orifices are located in one 40 wall while the opposite wall is provided with a pair of openings communicating with opposite ends of said passage and annular walls disposed about said openings at a distance therefrom, said walls being threaded on their inner circumferences; a closure plug adapted to extend into each opening and provided with an annular flange adapted to lap the main wall of the header about

the opening and to fit within the annular wall; the flange of the closure plug and the main wall of the header having complementary annular grooves; an annular gasket seatable and compressible in said complementary grooves; and pressure applying members dished on their inner faces and each provided with a rounded annular perimeter adapted to seat on the flange of the closure plug, said members having threaded perimeters adapted to screw into the annular walls 10 and thereby force the rounded perimeters into pressure applying relation with the flanges of the closure plugs at points substantially above the gasket receiving grooves in the flanges of said plugs. 15

2. In a return bend of the character described, the combination of a header provided with a return passage whose orifices are located in one wall while the opposite wall is provided with a pair of openings aligned with said orifices and 20 communicating with said passage, the header about each of said pair of openings being provided with an annular wall of greater circumferential dimensions than the diameter of the opening, said annular wall being threaded on its inner 25 perimeter and provided with a slot extending transversely of the threads from top to bottom of said wall; a closure plug of the deflector type adapted to extend into each opening and provided with an annular disc portion adapted to lap the 30 main wall of the header about the opening and to fit within the annular wall, said annular disc portion being provided with a radially disposed lug adapted to fit into the slot in the annular wall, the lower side of the disc portion and the 35 main wall of the header being provided with complementary annular grooves; an annular gasket seatable and compressible in said complementary grooves, and a cap-nut member having a dished inner face adapted to screw into each of said annular walls, the inner faces of said cap-nut members each formed with an annular protruding surface adapted to engage with the disc portion of the respective closure plug at a point substantially in alignment with said annular gasket. 40 45

HENRY E. MUCHNIC.
